APPARATUS FOR FIRING POWDER

Alfred Groth and Henry J. Hanauer,
Milwaukee, Wis.

Application January 11, 1943, Serial No. 471,972

5 Claims. (Cl. 35—25)

This invention relates to improvements in apparatus for firing powder.

In modern warfare it is frequently desirable for one side to attract enemy fire or to mislead enemy reconnaissance planes by exploding charges of powder in locations removed from the real artillery positions of the side employing the ruse of igniting sham charges.

Enemy airplanes, through the aforementioned ruse, are caused to drop bombs in the wrong locations and thus waste the same. In the case of enemy artillery, the same will be fired in the direction of the exploding sham charges to expose the enemy artillery positions. Thus, the real artillery of the troops employing this ruse may then effectively open fire on the enemy. The above mentioned practice is particularly effective at night when the flashes from the exploding powder are readily visible. The improved powder exploding devices may be set up in brush or other locations where the real character of said devices will be concealed. If used in an open area, however, the powder exploding devices may be set up adjacent to camouflage sham field pieces so that the usual effect of real artillery is simulated.

It is a general object of the present invention to provide a relatively small and inexpensive device for firing powder, which is automatic, relatively safe, and complete in itself.

A further object of the invention is to provide a device capable of handling powder charges of various sizes and nature for the simulation of the fire from various types of field pieces.

A further object of the invention is to provide a device of the class described in which the firing rate may be varied to simulate the firing rate of a particular type of field piece.

A further object of the invention is to provide a powder firing device constructed to operate with charges of powder contained in spherical capsules and constructed to accommodate and feed capsules of varying sizes.

Other objects of the invention are to provide powder firing apparatus and charges therefor wherein the powder charges are relatively safe to handle and ship, wherein the apparatus is readily portable and of a size to occupy little shipping space, and wherein the value of the apparatus, if destroyed, is relatively small.

With the above and other objects in view the invention consists of the improved apparatus for firing powder, and all of the parts and combinations incident thereto, as set forth in the claims, and all equivalents thereof.

In the accompanying drawing in which the

same reference characters indicate the same parts in all of the views:

Fig. 1 is a side view, with parts broken away and in vertical section, of the improved apparatus for firing powder, with the wiring arrangement shown schematically;

Fig. 2 is a fragmentary, detail view, partly in section, showing the powder charge magazine and the means for controlling the advancement of successive powder charges, the latter being in a position different from that of Fig. 1;

Fig. 3 is a fragmentary side view of a modified form of the invention, with portions broken away and in section;

Fig. 4 is a transverse sectional view taken on line 4—4 of Fig. 3, and on a larger scale; and

Fig. 5 is an enlarged sectional view of a typical powder capsule or charge.

Referring now more particularly to the drawing it will appear that the numeral 10 indicates a box-like casing rigidly mounted on the rear end portion of a flat horizontal base 11. Mounted on the forward end of the base is an upright bracket 12 rigidly supporting a firing barrel 13 in a desired forwardly, upwardly inclined position. The raised forward end of the barrel is open while the lower rear end is screw-threaded, as at 14, and is closed by means of a removable cap 15, screwed onto the barrel portion 14. On the inner face of the cap 15 there is an electrical heating element 16 held in position by terminal screws 17 to which are secured circuit wires 18 and 19. Insulation 20 separates the head ends of the screws from the cap 15.

In the form of the invention shown in Fig. 1 an elongated hollow magazine 21 is supported in the casing 10, extending substantially forwardly thereof and inclined forwardly, downwardly. The outer end of the magazine carries a pellet or capsule directing snout 22 which is curved and downwardly directed and disposed immediately vertically over the open end of the barrel 13, having a directing flange or finger 23. The inner open end of the magazine 21 communicates with the bore of a cartridge holding block 24. The latter extends exteriorly of an upper rear portion of the casing 10 and its bore is inclined, as shown. An opened end portion of a cardboard or the like cartridge 25 is adapted to be inserted into the bore of the block 24. As the cartridge, which is removable and replaceable when its contents are exhausted, contains a plurality of spherical powder capsules or pellets 26, the latter are free to roll or gravitate from the open end of the cartridge 25, through the block 24 and into and

down the inclined magazine 21. The powder capsules or charges 26 will be described more fully hereinafter.

Housed within the casing 10 is a dry-cell battery 27, preferably of nine volts. From the terminals 28 and 29 respectively of said battery extend the circuit wire 18 previously mentioned, and another circuit wire 30 off of which the wire 19 is tapped. Through this arrangement the heating element 16 in the base of the barrel 13 is energized and the circuit to the heating element is controlled by a switch 31 conveniently mounted on an exterior portion of the casing 10.

A small electric motor 32 is mounted on the base 11 forwardly of the casing 10. The motor's terminals have connected thereto the circuit wire 30 as well as a wire 33 tapped off of the wire 18. Included in the motor circuit is a motor control switch 34 and a rheostat 35, both of which are conveniently mounted on an exterior portion of the casing 10.

Mounted on a gear reduction box 36 adjacent the motor 32 is a shaft 37 carrying fast thereon a disc 38. Motion, at a desired speed, is transmitted from the motor shaft 39 to the shaft 37 by conventional reduction gearing housed within the box 36. A wrist pin 40 on the disc 38 pivotally carries one end of a connecting rod 41 which is also pivotally connected to one end of a gate and stop member 42. The main extent of the member 42 which is a gate-forming plate 43 extends slidably through a slot in the bottom wall of the magazine 21 and outwardly through an enlarged slot 44 in the top wall of said magazine, being adapted to be reciprocated relative to the magazine. A portion of the plate 43 which registers with the interior opening through the magazine is formed with an aperture 45, somewhat larger than the capsules 26. Depended from the top of the member 42 through the slot 44 and adjustably spaced forwardly of the plate 43 is a capsule stop flange 46.

One typical exemplification of a powder filled capsule or pellet is shown in detail in Fig. 5. There, a charge or batch of suitable ignitable powder 47 is packed within a spherical capsule or two-part shell 48 formed of a readily inflammable, nitro-cellulose material such as Celluloid. The capsules or pellets are preferably spherical so as to roll and gravitate easily and evenly. They may be of any desired size within certain limitations, but should be substantially smaller than the opening through the magazine so as to move freely therein. In practice a desired number of similar pellets may be packed within a cartridge 25. For different uses and purposes the types of powder charges in capsules may be varied to obtain flashes, smoke or explosions of desired colors and appearances, for the simulation of the firing effect of specific types of guns and artillery pieces.

The improved powder firing apparatus is light, compact and readily portable. For the latter purpose the top of the casing 10 is equipped with a carrying handle 49. The apparatus is intended for warfare use for the purpose of attracting enemy fire toward erroneous locations and to mislead enemy reconnaissance aircraft. Customarily one or more of the improved devices may be set up and hidden in desired locations remote from the user's real positions. The devices are susceptible of automatic operation for a desired period of time. It is also a practice in modern warfare for one body to attempt to mislead the enemy as to the strength, number and location

of its heavy artillery and anti-aircraft guns to install sham artillery pieces and guns in certain locations. With the present invention the sham may be furthered by strapping the improved powder firing devices under the fake guns. Thus, when the devices are set into operation and powder charges are fired, the sham guns will have an even greater realistic appearance and effect.

From the description thus far given the operation of the improved powder firing apparatus is no doubt obvious. After the device is set up in a desired location, a pellet-containing cartridge 25 is registered with the upper end of the magazine 21, as in Fig. 1. Both of the switches 31 and 34 should be turned to "on" positions, whereupon the circuits from the battery 27 will energize the electric motor 29 and the heating element 16 within the base of the barrel 13. The powder filled capsules or pellets 26 will, in the principal form of the invention, continuously gravitate down the inclined magazine 21. Through the motor 32 and the connections to the disc shaft 37 the disc 38 will be continuously rotated to reciprocate the connecting rod 41. When the connecting rod is in a raised position, as in Fig. 1, the gate plate 43 of the member 42 will be raised to remove from the path of travel of the pellets the aperture 45, whereby a solid portion of the gate plate will engage and temporarily restrict movement of the forwardmost pellet. In this position the capsule stop flange 46 is likewise raised and is out of the path of travel of the capsules or pellets. Then, when the disc 38 turns further to downwardly reciprocate the connecting rod 41, the arrangement will be as is shown in Fig. 2, whereupon the forwardmost pellet 26 may pass through the aperture 45 of the gate plate 43 and roll down the magazine toward the discharge end thereof. The pellet next in line will be engaged and temporarily blocked from further movement by the lowered stop flange 46. When the released pellet reaches the lower open end of the magazine, it passes through and out of the snout 22 and is then permitted to drop vertically into the open mouth of the barrel 13. The released capsule or pellet eventually rolls to the closed lower end of the barrel and lodges against the heating element 16. The heat from this element will ignite the capsule shell 48 and cause a burning or explosion of the powder 47 within the shell. Such action will produce a flash and smoke emanating from the open mouth of the barrel such as will simulate the firing effect of a real gun or field piece. As previously mentioned, the type and color of the powder within a capsule will produce the desired effect as to flash and smoke for the simulation of any given gun or field piece whether it be an anti-aircraft gun, a howitzer, or field or artillery piece. Different types of guns and field pieces fire at different rates of speed. For this purpose the rheostat 35 in the circuit to the electric motor 32 may be employed to either speed up or retard the operation of the motor. Such action will of course vary the speed of reciprocation of the member 42 regulating the discharge of the individual capsules or pellets 26.

A modification of the means for the individual controlled feed of powder-containing capsules or pellets to the barrel 13 is shown in Figs. 3 and 4. The barrel 13 and its appurtenances is similar to that shown and described in connection with the principal form of the invention and it is similarly mounted on a base 12 in association with a battery-containing casing. Associated with the cas-

ing is an angularly shaped magazine 21', the rear end portion of the magazine being forwardly downwardly inclined to receive pellets 26 from a cartridge while the outwardly and forwardly directed portion of the magazine 21' is preferably slightly upwardly inclined. Successive timed movement of pellets 26 through the forward portion of the magazine and discharge therefrom into the firing barrel 13 is accomplished by an endless conveyor 50 extended about guide rollers 51 mounted fast on spaced apart transverse shafts 52 underlying the forward extent of the magazine. The endless conveyor is provided with spaced apart flights 53 which, on the upper extent of the conveyor, project substantially through a longitudinal slot 54 in the bottom wall of the magazine. The forward and downward gravitation of pellets in the rear and inclined extent of the magazine 21' is terminated by protuberances 55 which engage the forwardmost pellets and ordinarily prevent further movement of the same. However, during operation of the conveyor, a flight will traverse the rear roller 51 and come into position so as to engage the forwardmost pellet and will move the same over the protuberances and along the forward extent of the magazine, as shown in Fig. 3. The endless conveyor shaft 52 may be driven by means of suitable connections with an electric motor 32, as in Fig. 1, or a conventional counterweight drive may be used for operating the conveyor.

From the foregoing description it will be seen that the improved apparatus for firing powder is simple, effective, and economical.

Various changes and modifications may be made in the apparatus for firing powder, without departing from the spirit of the invention, and all such changes are contemplated as come within the scope of the appended claims.

What is claimed as the invention is:

1. In combination, an inclined barrel having an open upper end and a closed lower end, a heating unit within the closed end of the barrel, an explosive powder pellet magazine disposed over the barrel and having an open discharge end positioned adjacent the open end of the barrel and having a cartridge holder at its other end, a powder pellet cartridge removably mounted in said holder, powder pellets being adapted to gravitate from the cartridge into the magazine in alinement, and means for automatically advancing pellets in timed sequence along said magazine to the open outer end thereof from whence the same gravitate from the open end of the magazine into the barrel for ignition and explosion by said heating unit.

2. In combination, an inclined barrel having an open upper end and a closed lower end, a heating unit within the closed end of the barrel, an explosive powder pellet magazine disposed over the barrel and having an open discharge end positioned vertically over the open end of the

barrel and having a cartridge holder at its other end, pellet stop means within the magazine, a powder pellet cartridge removably mounted in said holder from whence powder pellets gravitate in alinement into said magazine against said stop means, and means for advancing the forwardmost pellet beyond the stop means toward the open outer end of the magazine from whence the same gravitates into the barrel for ignition and explosion by the influence of said heating unit.

3. In combination, an inclined barrel having an open upper end and a closed lower end, a heating unit within the closed end of the barrel, an explosive powder pellet magazine disposed over the barrel and having a discharge end positioned adjacent the open end of the barrel, vertically reciprocable pellet stop means controlling the magazine, powder pellets being adapted to roll in alinement in said magazine against said stop means, and automatically operating, regulatable means for reciprocating the stop means to permit advancement of the forwardmost pellet from the open outer end of the magazine from whence the same gravitates into the barrel for ignition and explosion by the influence of said heating unit.

4. A powder exploding apparatus comprising, a base, an inclined barrel mounted thereon and having an open upper end and a closed lower end, a heating unit within the closed end of the barrel, an explosive powder pellet magazine supported on the base and having an open discharge end adjacent the open end of the barrel, a plurality of inflammable powder pellets being supplied to the magazine, mechanical means automatically controlling the advancement of successive individual pellets through the open discharge end of the magazine, and a motor for operating said mechanical means.

5. A unitary portable powder exploding apparatus comprising, a flat base, an upright casing mounted on a rear portion of said base, an inclined barrel mounted on the base forwardly of the casing, said barrel having an open upper end and a closed lower end, an electric heating unit within the closed end of the barrel, an explosive powder pellet magazine mounted on an upper portion of the casing and having a discharge opening adjacent the open end of the barrel, the magazine containing a plurality of inflammable powder pellets, regulatable mechanical means controlling the advancement of successive individual pellets along the magazine and out of the open discharge end thereof, an electric motor supported on the base and operatively connected with said mechanical means, a battery housed within the casing, and electrical connections between the battery and heating unit and motor.
